UNITED STATES PATENT OFFICE

2,584,624

DOOR

Percival H. Sherron, Jamaica, N. Y.

Application February 26, 1948, Serial No. 11,099

3 Claims. (Cl. 160—232)

1

This invention relates to a door and more particularly to a door of the type suitable for use in various structures such as, for example, a telephone booth.

In general, the broad object of this invention is to provide a door comprised of elements which may be rapidly fabricated in quantity and assembled with ease by unskilled workmen.

A further object of this invention is to provide a door having a minimum number of individual parts without any sacrifice of structural strength.

An additional object of this invention is to provide a folding leaf door with interlocking hinges which eliminate the necessity of using separate hinges.

A further object of this invention is to provide a structurally strong door which may be formed without the use of welding, soldering or brazing.

A further object of this invention is to provide a door having novel means for securing a window therein.

The novel features of design and structure, by means of which these and other objects which will become apparent are accomplished, may be best described in connection with the accompanying drawings which show an embodiment of this invention adapted for use in connection with a telephone booth.

In the drawings:

Fig. 1 is a face view of a completed double leaf door as viewed from the rear;

Fig. 2 is a section taken on the plane indicated by the line 2—2 in Fig. 1;

Fig. 3 is a section taken on the plane indicated by the line 3—3 in Fig. 1;

Fig. 4 is an elevation of a blank used to make the inside panel of the right hand leaf of the door as viewed in Fig. 1.

Fig. 5 is an elevation of a blank used to make the outside panel of the right hand leaf of the door as viewed in Fig. 1.

Fig. 6 is an elevation of a blank used to make the outside panel of the left hand leaf of the door as viewed from the rear;

Fig. 7 is an elevation of a blank used to make the inside panel of the left hand leaf of the door as viewed from the rear;

Fig. 8 is a rear perspective view of the completed panels which, when assembled, will form the right hand leaf of the door;

Fig. 9 is a sectional view of a moulding strip used to hold a pane of glass; and

Fig. 10 is a section taken looking down on a horizontal plane through a telephone booth below the lintel to show how the double leaf door may be installed in a telephone booth.

2

All references to the left or right hand in the following description are based on a view taken from the rear of the door as in Fig. 1.

A door 2 has a right hand leaf 4 and a left hand leaf 6. Leaf 4 has a front panel 3 and a rear panel 5. Leaf 6 has a front panel 7 and a rear panel 9. The panels 3, 5, 7 and 9 are formed from stampings 10, 8, 12 and 14, respectively, which are shown in Figures 4 through 7.

In order to form the right hand leaf 4, rear panel 5 is first formed from stamping 8 shown in Figure 4. The stamping 8 is bent at right angles along the dotted lines indicated at 16 and 18 to form horizontal flanges 20 and 22, respectively (Figure 8). By bending the blank 8 at right angles along the dotted line indicated at 24, a vertical flange 26 is formed. The flange 26 is then bent along the dotted line 28 to form a small flange 30 perpendicular to the flange 26. This rear panel is completed by bending the blank along the line 32 to form the hinge portion 34 and by bending the ears 35 to form cylindrical pin-receiving hinges 37.

The front panel of the right hand leaf 4 is formed by first bending the blank 10 (Figure 5) at right angles along the dotted lines indicated at 36 and 38 to form horizontal flanges 40 and 42, respectively (Figure 8). These flanges are then bent along the dotted lines indicated at 44 and 46 to form vertical flanges 48 and 50.

The blank 10 is then bent along the dotted line 52 to form the substantially U-shaped opening 54. This exterior panel is completed by bending ears 56 to form cylindrical pin-receiving hinges 58.

As shown in Figure 8, the completed panels 3 and 5 are positioned for assembly. In order to assemble these panels, panel 3 is moved to the left in such a manner that the flange 40 will slide over the flange 20 and the flange 42 will slide under flange 22. When the assembly is completed, flanges 48 and 50 bear against face 60 of panel 5, and flange 30 fits securely in the U-shaped opening 54. In addition, the hinges 58 are aligned with the hinges 37 and hinge panel 34 abuts against panel 3. Further, window opening 62 in panel 5 and an opening 64 in panel 3 are now positioned opposite each other.

The blanks 12 and 14 and the panels 7 and 9 formed therefrom are mirror images of blanks 10 and 8 and panels 3 and 5, respectively, with the exception that the hinges 66 and panel 7 and the hinges 68 of panel 9 are located so as to be alignable with and fill the spaces between pairs of hinges 37 and 58. The formation of panels 7 and 9 is consequently identical to the for-

mation of the above described panels 3 and 5. The exterior panel 7 is formed by bending the blank 12 at the lines indicated at 70, 72, 74, 76 and 78 to form flanges 80 and 82, U-shaped opening 84, flanges 86 and 88, respectively (Figures 1-3). Ears 90 are bent to form hinge 66.

The inner panel 9 is formed in a manner similar to the formation of inner panel 5 by bending the blank 14 along the lines indicated at 92, 94, 96, 98 and 100 to form flanges 102, 104, 106, 108 and hinge panel 110, respectively (Figures 1-3). Ears 112 are bent to form hinge 68.

The panels 7 and 9 are assembled to form the leaf 6 by sliding the panels together until the hinges 66 and 68 are aligned and flange 108 is locked in the opening 84.

In order to complete the formation of the door 2, the aligned hinges 31 and 58 of leaf 4 are brought into alignment with the aligned hinges 66 and 68 of the leaf 6. A hinge pin 114 having a knob 116 is driven downwardly through the hinges. It should be noted that the hinge pin is not only utilized for hingedly connecting the leaves 4 and 6 but also acts to lock panels 3 and 5 and panels 7 and 9 to each other respectively.

To secure a pane of glass in each leaf, a novel molding strip 118 formed of any flexible rubber-like material is utilized. The molding strip 118 has on its inside 120 a pair of slots 122 and 124 which are of the same width as the sheet metal used to form the doors and are spaced apart a distance equal to the space between the front and rear panels of a leaf. The outside 126 has a slot 128 suitably formed to receive a pane of glass 130.

As shown in Figure 3, molding strip 118, which is used in the left hand leaf, holds a pane of glass 130 in slot 128, while, in turn, the strip itself is held in position by virtue of the fact that the panels 9 and 7 are entered in slots 124 and 122, respectively. Due to the flexible nature of the molding strip, glass 130 may be secured in position without difficulty by following the method of working the glass 130 into slot 128 and the panels 9 and 7 into slots 124 and 122 progressively. Thus, as the molding strip is secured to a small portion of the leaf, that portion of the pane of glass which is opposite the part of the leaf secured in the strip is forced into slot 128. By following this procedure in successive increments, a pane of glass 130 may be secured in the door without difficulty.

The door 2 may be secured in a telephone booth structure 132 in any of the conventional manners of securing a double leaf door in a telephone booth such as, for example, by the means shown in my prior Patent No. 2,208,166, issued July 16, 1940, which is illustrated in Figure 10. As shown, a bracket 134, which is secured to leaf 4, carries a roller 136 which travels in track 138. Track 138 is secured to walls 139 and 141. The leaf 6 is secured to wall 143 of the telephone booth 132 by hinge 140. A knob 142 is secured to leaf 4 to provide means for opening and closing the door from the interior of the telephone booth.

It will, of course, be obvious from the embodiment here illustrated and described that a single leaf door may be formed in accordance with this invention. In the case of a single leaf door, the aligned hinges of the panels forming the leaf are utilized to hingedly secure the door to the supporting structure.

It will be evident that the features of the invention may be embodied in structures other

than that illustrated, and accordingly the invention is not to be regarded as restricted except as required by the following claims.

What I claim and desire to protect by Letters 5 Patent is:

1. A door having two leaves, each leaf having a pair of spaced panels, hinges on the panels formed integrally therewith which are in alignment, and a hinge pin passing through the hinges of all the panels thus locking both the panels and the leaves together, each of said pairs of panels being additionally locked together along their other sides by abutting and interlocking flanges.
2. A door comprising a first panel having along each vertical and horizontal edge an inwardly extending flange, integral hinge members on the vertical edge of one of said flanges extending inwardly from one vertical edge of the panel and a locking flange extending from the inner edge of the flange extending inwardly from the second vertical edge of the panel, a second panel having an L-shaped flange extending from the top edge so as to overlie the top flange of the first panel and lie against the face of the first panel, an L-shaped flange extending from the bottom edge so as to lie under the bottom flange of the first panel and against the face of the first panel, integral hinges along one vertical edge which are aligned with the hinges of the first panel, a slot for the reception of the locking flange and a hinge pin through the hinges.
3. A door having two leaves, each leaf comprising a first panel having along each vertical and horizontal edge an inwardly extending flange, integral hinge members on the vertical edge of one of said flanges extending inwardly from one vertical edge of the panel and a locking flange extending from the inner edge of the flange extending inwardly from the second vertical edge of the panel, a second panel having an L-shaped flange extending from the top edge so as to overlie the top flange of the first panel and lie against the face of the first panel, an L-shaped flange extending from the bottom edge so as to lie under the bottom flange of the first panel and against the face of the first panel, integral hinges along one vertical edge which are aligned with the hinges of the first panel, and a slot for the reception of the locking flange, all of the hinges of the four panels being aligned and having a hinge pin passing through them so as to hingedly connect the leaves together.

PERCIVAL H. SHERRON.
